BRUSH

Curt Neufeld, Fairview, N. J.

Application July 9, 1935, Serial No. 30,450

5 Claims. (Cl. 42—91)

This invention relates to brushes, and more particularly to brushes for use as gun swabs.

The objects of the invention are to provide an improved brush as characterized; to provide a brush which will clean the bore rifling; to provide a brush which will not bind when reversing its direction of cleaning motion; to provide a metal body for the brush; to enable the bristles to be replaced when worn; to provide for adequate gripping area on the handle; to provide a light but sturdy structure; to secure simplicity of construction and perfection in operation; and to obtain other advantages and results as may be brought out in the following description.

15 Referring to the accompanying drawing in which like numerals of reference indicate similar parts throughout the several views;

Figure 1 is an elevation of a brush for use as a gun swab constructed in accordance with the present invention;

Figure 2 is a similar elevation of the brush revolved ninety degrees from the position shown in Fig. 1;

Figure 3 is a central longitudinal section of the brush, as upon line 3—3 of Fig. 2;

Figure 4 is an elevation of the body portion of the brush with the removable section thereof taken off; and

Figure 5 is an end view of the portion of the brush shown in Fig. 4.

In the specific embodiment of the invention illustrated in said drawing, the reference numeral 1 indicates the body portion of the brush, which is shown as having a main body section 2 and a removable complementary section 3 which together forms a complete cylindrical shape at the exterior with the outer end semi-spherical. The brush body provides clumps of bristles 4 entirely around the body portion and for a length of said body portion next the semi-spherical portion to the inner end of the complementary section. At the end of the complementary section last mentioned, the main section has a completely cylindrical shape thus providing a shoulder 5 against which the end of the complementary section will abut. Below the shoulder 5, said main section 2 provides a reduced cylindrical neck. The lower end of this neck is formed with an end cavity 6 symmetrical to the axis of the body and providing therein a seat 7 for a suitable ball-race or other anti-friction bearing 8. Said bearing is held in place by a collar 9 threaded into the lower end of the cavity. A stud 10 is mounted rotatably in the race to have both anti-friction rotatable motion and anti-friction thrust support.

The end of the stud projects from the lower end of the cavity, and is screw threaded to be applicable to the end of a handle 11. The handle is preferably of hollow aluminum or aluminum alloy tubing so as to be light and strong, and the end of the tubing is closed with a plug 12 at its end next the brush body portion so as to receive said stud in a suitably provided threaded hole axially disposed in the plug. Some such means as a lateral pin 13 may be employed to hold the 10 plug fast in the handle tubing.

It will be noted in the construction of the brush body portion, that the same is preferably hollow and of metal, aluminum or an aluminum alloy also being used by preference in order that the 15 body portion may be both light and strong. An aligning pin or the like 14 may be provided adjacent the outer end of one of the sections to fit within a female part, such as the hole 15 shown in the other section. The two sections are secured together by suitable means, such as the pair of diametrically disposed screw-bolts 16, 16, the heads of which are preferably countersunk. The outer end of the body portion is semi-spherical or dome-shaped by preference so that no damage can be done by it if engaged against the 20 gun bore in use, and further to aid in the introduction of the brush into a gun bore.

A particular feature of the present invention resides in the structure pertaining to the bristles. 30 It is to be observed first that the same are relatively short with respect to the diameter of the body portion of the brush. This enables me to use hair bristles and maintain adequate rigidity or stiffness to be effective upon the carbon or 35 other deposit in a gun bore. In the second place, the bristle clusters are arranged upon lines longitudinal of the body portion of the brush corresponding to the angle, line or curvature of the rifling provided in the bore of a gun. The clusters of bristles are thus in a plurality of longitudinal series and will thus tend to enter and follow the rifling in use. The anti-friction attachment of the brush body to the handle introduces the least possible interference with this action 45 of the brush following the twist of the rifling. The twist of the brush will reverse when withdrawing the brush, and this possible twisting as well as the flexibility of the bristles, lends itself to proper operation of the brush and avoids the 50 usual tendency in gun swabs to wedge in the bore when the direction of movement of the swab is reversed. This is of great importance in the art, and one of the most serious difficulties encountered in cleaning guns. The invention ap- 55

plies very particularly to guns of cannon caliber, that is, three to sixteen inches and even more in bore diameter, but is not limited thereto, as it may also be made and used for smaller sizes of bores.

5 I wish to also emphasize the fact that the brush body is of metal, this fact avoiding the deleterious effects of oil and other matter encountered in cleaning guns, and enabling the brush to be 10 washed with gasolene or other fluids without injury. The hollow construction also makes it economically practical to replace the bristles with new ones when required, thus keeping the brush in service for an indefinite length of time.

15 Having thus described the invention, I claim:

1. A brush as characterized, comprising a substantially cylindrical head, clusters of bristles projecting from the cylindrical surface of said head, said clusters of bristles being arranged to 20 project in longitudinal series the end clusters of each series toward one end of the head being substantially equally spaced around the head and constituting points through which pass theoretic 25 parallels to the axis of the head on the cylindrical surface of said head, said series being angular with respect to said parallels with the clusters having substantially equal spacing from each other within a series as the spacing between the clusters of one series and the next, and each 30 series starting upon one of said parallels which crosses a next adjacent series substantially midway of the length of said adjacent series.

2. A brush as characterized, comprising a substantially cylindrical head, clusters of bristles projecting from the cylinder in longitudinal series, the end clusters of each series toward one end of the head constituting points through which pass theoretic 35 parallels to the axis of the head on the cylindrical surface of said head, said series having angular relationship to said parallels to the axis of the head less than 10° and

substantially corresponding to the rifling of a gun bore.

3. A brush as characterized, comprising a substantially cylindrical and hollow metallic body portion having a main section and a complementary section of less length than said main section and having its length completed by a completely annular part of the main section, said completely annular part having an uninterrupted seat therein, a bearing on said seat, bristles in 10 said sections, and means for securing said sections separably together whereby the bristles may be renewed as required.

4. A gun swab comprising a brush body portion, a handle attached to said brush body portion 15 for manipulating the same, an anti-friction connection between said brush body and handle, and clusters of bristles arranged in series the end clusters of each of which series toward one end of the head constitute points through which pass 20 theoretic parallels to the axis of the head on the cylindrical surface of said head, said series all sloping with respect to said parallels and each series crossing a next adjacent parallel at a greater distance longitudinal of the parallel than the distance separating two alternate parallels 25 for rotating the brush body in use to follow the rifling of the bore of a gun being cleaned.

5. A brush comprising a substantially cylindrical head, clusters of bristles projecting from the cylindrical surface of said head in longitudinal series, the end clusters of each of which series toward one end of the head constitute points through which pass theoretic parallels to the axis of the head on the cylindrical surface of said head, said series all sloping with respect to said 30 parallels and each series crossing a next adjacent parallel at a greater distance longitudinal of the parallel than the distance separating two alternate parallels. 35
